CLAIM

The ornamental design for a tuner for a guitar pickup, as
shown and described.

DESCRIPTION

FIG. 1 is a top, front and right side perspective view of
a tuner for a guitar pickup showing my new design;

FIG. 2 is a left side elevational view thereof;

FIG. 3 is a top plan view thereof, rotated 180 degrees
from FIG. 1; and

FIG. 4 is a rear elevational view thereof.

The bottom is plane and unornamented.
